BOILER

Bernard Goerg, Scarsdale, N. Y., assignor, by
mesne assignments, to American Radiator &
Standard Sanitary Corporation, New York,
N. Y., a corporation of Delaware

Application January 8, 1938, Serial No. 183,957

7 Claims. (Cl. 122—225)

My invention relates to improvements in heating apparatus for house heating purposes, and the same has for its object to provide a boiler which is simple in construction, convenient to manufacture, and efficient and economical in operation.

Further, said invention has for its object to provide a boiler adapted for burning oil, and more particularly for efficiently burning oil by means of a burner of the gun type.

Further, said invention has for its object to provide a boiler of the type specified which shall be compact in form, light in weight, and easy to assemble and erect.

Further, said invention has for its object to provide a boiler in which the form, size and proportion of the combustion chamber in relation to the size and arrangement of the flues leading therefrom to the stack is such as to insure the highest efficiency of operation.

Further, said invention has for its object to provide a boiler in which the hot gases and products of combustion on leaving the fuel receptacle and combustion chamber will be deflected and radially diverted to an extent substantially equal to the height of the flue through which the same are then carried to the smoke outlet.

Other objects will in part be obvious, and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawings—

Figure 1 is a front view showing one form of jacketed boiler constructed according to and embodying my said invention;

Fig. 2 is a side elevation of the jacketed boiler;

Fig. 3 is a back view of the jacketed boiler;

Fig. 4 is a front view of the boiler with the jacket removed;

Fig. 5 is a side elevation with the jacket removed;

Fig. 6 is a back view of the boiler without the jacket;

Fig. 7 is a horizontal section on the line 7—7 of Fig. 5;

Fig. 8 is a face view of the front section;

Fig. 9 is an inside face view of the back section, and

Fig. 10 is a face view of an intermediate section.

In said drawings 10 designates the boiler as a

whole which is shown comprising a series of transverse sections including a front section 11, a back section 12, and a plurality of intermediate sections 13, which are communicatively connected at their upper corners by large nipples 14, and at their diagonally opposite lower corners by smaller nipples 15. The sections 11, 12 and 13 are provided on their opposite faces with peripheral beads 11^a, 12^a, 13^a, and interior beads 11^b, 12^b, 13^b, respectively, and are secured in assembled relation by tie rods 10^a.

The said sections 11, 12, 13 are essentially rectangular in form and each provided with a depending portion 16 at one of its lower corners with openings in which the lower nipples 15 are fitted. The interior of said depending portions 16 together with the nipples 15 secured therein form a mud drum 17. The opposite lower corners of the assembled sections are supported in raised position by two or more legs or standards 20

18. The front section 11 is provided at one side adjacent to its lower end with a circular fuel opening 19 provided with a closure 20 secured in position by bolts 21. The closure 20 is provided with a central aperture 22 adapted to receive the nozzle of an oil burner. The front section is also provided at its opposite side on about the same horizontal plane with the fuel opening 19 with a vertical clean-out opening 25 having a closure 26 which is secured in position over said opening 25 by latches 27 pivotally secured to the front section.

Each intermediate section has a large circular opening 28 adjacent to one of its sides occupying the greater part of the section and registering with corresponding openings 28 of the other intermediate sections, and with the recess 28^a in the back section 12, and with the opening 19 in the front section to form the longitudinal, cylindrical fuel receptacle and combustion chamber 29 which is preferably provided with a refractory lining 29^a. The openings 28 of the intermediate sections are enclosed at their opposite sides with registering hollow segmental, water-backed wall portions 30, 31 which merge at their lower ends with the water-backed horizontal base member 32, and at their upper ends with the relatively deep dome portion 33 which extends entirely across the upper portion of the boiler.

At the side of each of said intermediate sections between the curved wall portion 31 of the fuel receptacle and combustion chamber and the vertical peripheral water leg 34 is a vertical flue opening substantially coextensive in height of the

fuel receptacle and combustion chamber 28, having a central vertical water leg 35 therein communicating at its upper end with the dome portion 33, and at its lower end with the depending mud drum portion 17. The said water leg 35 registers with the corresponding water legs of adjoining intermediate sections, and the member 35^a of the back section 12, and forms jointly therewith a longitudinal partition serving to divide said vertical flue opening into a forwardly extending flue 36 and a rearwardly extending flue 37 which latter communicates at its outlet end with the registering smoke outlet opening 38 in the back section 12.

15 The flues 36 and 37 register at their forward ends with the clean-out opening 25 in the front section 11, and are provided upon their vertical and horizontal wall portions with fins or extended surface members 39 which cooperate with those of the adjoining sections and form longitudinal baffles to insure the efficient distribution of the hot gases and products of combustion throughout said flues, and the maximum abstraction of the heat thereby.

20 The back section 12 is provided upon its inner wall at the junction of the fuel receptacle and combustion chamber with the intake end of the flue 36 with a series of radial ribs 40 arranged in the arc of a circle whereby the hot gases and products of combustion produced or liberated in the combustion chamber will be deflected in their passage and caused to flare or spread so that the same will, upon entering the intake end of the flue 36, completely fill the same from top to bottom, and continue so through the flues 36 and 37 to the smoke outlet 38.

25 Upon the outer wall of the back section 12, directly over the smoke outlet 38 is bolted a smoke hood 46 comprising a tubular portion 47 communicating with the upper portion of the smoke outlet 38, and a tapering pouch portion 48 depending from said tubular portion 47 communicating with the lower portion of said smoke outlet 38. The tubular portion 47 is provided with a reduced free end 49 adapted for attachment to a smoke pipe or stack.

30 The back section 12 is provided in its rear or outer wall portion with a cut-out portion 50 over which is disposed a semi-cylindrical cover 51 secured in place by bolts 52. The said cut out portion 50 and its cover 51 form a receptacle or casing for a hot-water coil or heater having one end connected to the intake pipe 53 communicating with a source of cold water supply, and to its other end connected to the outlet pipe 54 communicating through the pipe 62 with the hot water supply tank 61.

35 The said rear wall is also provided with a smaller cut-out portion 55 to receive a water control device, not shown, over which is disposed a recessed cover 56 having an aperture 56^a therein for connection with the source of water supply of the boiler. The said cover is secured in position by bolts 57. The said cut-out portion 55 and its cover 56 form a receptacle or casing to accommodate an automatic device for controlling the supply of water to the boiler.

40 The back section 12 is provided at its top with an outlet or flow nozzle 58 adapted to be connected to the supply line of the heating system, and at its opposite lower end said back section is provided with return inlet 16^a adapted to be connected to the return line extending from the heating system.

45 The back section 12 is further provided centrally with respect to the fuel receptacle and com-

bustion chamber 29 with an aperture 59 normally closed by a cover 60 through which the operation of the oil burner may be observed.

5 The front section 11 and the back section 12 are provided at their upper ends adjacent to one of their vertical surfaces and about midway between their opposite vertical surfaces with upwardly extending projections 11^c, 12^c forming saddles between which is supported a hot water supply tank 61. The pipe 62 connects the coil of the hot water heater contained within the cut out portion or compartment 50 of the back section 12 with the intake port of the hot water supply tank 61. The hot water supply tank is provided at its top with an outlet pipe 63 leading to the ultimate discharge valves or faucets, not shown, and with a circulating pipe 64 communicating with the cold water intake pipe.

10 The boiler and hot water supply tank are preferably enclosed in a sheet metal jacket 64', having an opening 65 in its front of sufficient size to allow free access to the fuel receptacle and combustion chamber 29, and the flues 36 and 37. The said opening 65 is provided with a closure panel 66 held in place at its lower edge by clips 67, and at its upper edge by fastening devices 68. Both the clips 67 and fastening devices 68 are engageable with the inner side of the jacket front along the edges of said opening. Above said opening 65 the jacket front is provided with smaller openings 69 and 70 for the indicating devices, and water gage glass respectively. The jacket back and the top are also provided with suitable openings for the smoke hood 46, flow and return connections 58, 16^a, and other devices and parts, as required.

15 Having thus described my said invention what I claim and desire to secure by Letters Patent is:

1. A boiler of the character described comprising a plurality of communicatively connected sections including front, back and intermediate sections enclosing a horizontally-extending fuel receptacle and combustion chamber, and a plurality of vertical flues connecting said fuel receptacle and combustion chamber with the smoke outlet of the boiler; said flues and said fuel receptacle and combustion chamber being arranged vertically side by side and extending longitudinally of the boiler from the front to the back thereof, radial deflecting means on said back section at the rear end of said fuel receptacle and combustion chamber for spreading the hot gases and products of combustion vertically coextensively with the height of said flues, and a dome overlying the upper ends of said flues and said fuel receptacle and combustion chamber.

20 2. A boiler of the character described comprising a plurality of communicatively connected sections including front, back and intermediate sections enclosing a horizontally-extending fuel receptacle and combustion chamber, and a plurality of vertical flues connecting said fuel receptacle and combustion chamber with the smoke outlet of the boiler; said flues and said fuel receptacle and combustion chamber being arranged vertically side by side and extending longitudinally of the boiler from the front to the back thereof, a segmental series of radially disposed ribs on said back section at the junction of said fuel receptacle and combustion chamber with the entrance to said flues for causing the hot gases and products of combustion to spread vertically coextensively with the height of said flues, and a dome portion overlying the upper ends of said flues and said fuel receptacle and combustion chamber.

3. A cast-metal boiler comprising end and intermediate water-containing sections arranged in side-by-side relation with the end sections forming the front and rear of the boiler; said sections being formed to provide a combustion chamber completely enclosed by water-contained parts and extending from front to rear and along one side of the boiler; said sections being also formed to provide a pair of relatively narrow upright flues of approximately the same height as said combustion chamber and being arranged in side-by-side relation and along one side of said chamber and being connected for series flow of combustion gases from said chamber; said sections having nipple connections at their upper and lower portions respectively for circulation of water therebetween; and each of said intermediate sections comprising an upper dome portion extending across the top thereof, a mud drum portion in the lower part thereof, and a plurality of spaced water leg portions connecting said dome and mud drum portions and defining said combustion chamber and said flues respectively.

4. A cast-metal boiler comprising end and intermediate water-containing sections arranged in side-by-side relation with the end sections forming the front and rear of the boiler; said sections being formed to provide a combustion chamber completely enclosed by water-contained parts and extending from front to rear and along one side of the boiler; said sections being also formed to provide a pair of relatively narrow upright flues of approximately the same height as said combustion chamber and being arranged in side-by-side relation and along one side of said chamber and being connected for series flow of combustion gases from said chamber; each of said sections being substantially rectangular in outline with the sides thereof approximately equal in length; said sections having nipple connections at their upper and lower portions respectively for circulation of water therebetween; and each of said intermediate sections comprising an upper dome portion extending across the top thereof, a mud drum portion in the lower part thereof, and a plurality of spaced water leg portions connecting said dome and mud drum portions and defining said combustion chamber and said flues respectively.

5. A cast-metal boiler comprising end and intermediate water-containing sections arranged in side-by-side relation with the end sections forming the front and rear of the boiler; said sections being formed to provide a combustion chamber completely enclosed by water-contained parts and extending from front to rear and along one side of the boiler; said sections being also formed to provide a pair of relatively narrow upright flues of approximately the same height as said combustion chamber and being arranged in side-by-side relation and along one side of said chamber and being connected for series flow of combustion gases from said chamber; said sections having nipple connections at their upper and lower portions respectively for circulation of water therebetween; and each of said intermediate sections comprising an upper dome portion extending across the top thereof, a mud drum portion in the lower part thereof, and a plurality of spaced water leg portions connecting said dome and mud drum portions and defining said combustion chamber and said flues respectively.

6. A cast-metal boiler comprising end and intermediate water-containing sections arranged in side-by-side relation with the end sections forming the front and rear of the boiler; said sections being formed to provide a combustion chamber completely enclosed by water-contained parts and extending from front to rear and along one side of the boiler; said sections being also formed to provide a pair of relatively narrow upright flues of approximately the same height as said combustion chamber and being arranged in side-by-side relation and along one side of said chamber and being connected for series flow of combustion gases from said chamber; each of said sections being substantially rectangular in outline with the sides thereof approximately equal in length; said sections having nipple connections at their upper and lower portions respectively for circulation of water therebetween; and each of said intermediate sections comprising an upper dome portion extending across the top thereof, a mud drum portion in the lower part thereof, and a plurality of spaced water leg portions connecting said dome and mud drum portions and defining said combustion chamber and said flues respectively; and a liner for said combustion chamber formed of heat-resistant material and being supported interiorly of the water leg portions providing said chamber.

7. A cast-metal boiler comprising end and intermediate water-containing sections arranged in side-by-side relation with the end sections forming the front and rear of the boiler; said sections being formed to provide a combustion chamber completely enclosed by water-contained parts and extending from front to rear and along one side of the boiler; said sections being also formed to provide a pair of relatively narrow upright flues of approximately the same height as said combustion chamber and being arranged in side-by-side relation and along one side of said chamber and being connected for series flow of combustion gases from said chamber; said sections having nipple connections at their upper and lower portions respectively for circulation of water therebetween; and each of said intermediate sections comprising an upper dome, a lower mud drum, a pair of outside marginal water legs connecting the dome and mud drum, and a pair of spaced interiorly disposed water legs also connecting said dome and mud drum; one of said marginal water legs and the adjacent interior water leg defining the combustion chamber with said one marginal water leg forming the outside and extending across the lower part of said chamber; and the other of said marginal water legs and both of said interior water legs forming said flues.

BERNARD GOERG.
